TUBE-FORMING MACHINE

Rex E. Moule, Detroit, Mich.

Application March 28, 1938, Serial No. 198,614

2 Claims. (Cl. 18—19)

This application relates to machines for making gelatin tubing from which fluid-filled gelatin capsules may be made.

For an understanding of the machines herein disclosed reference should be had to the accompanying drawing.

In the drawing:

Fig. 1 is a plan view of a multiple mandrel—two strip construction;

Fig. 2 is an elevation view of Fig. 1 with parts 10 omitted;

Fig. 3 is a section on line 2—2 of Fig. 1;

Fig. 4 shows a mandrel in bottom plan view.

The drawing shows an apparatus for transforming two substantially flat strips 114 of gelatinous material into a tube or simultaneously into a plurality of tubes. In this construction, there are a plurality of hollow mandrels 115 located between spaced pairs of disks 112. These disks are mounted upon and fastened to axles or shafts 111 so that they may be rotated in the process of forming the tubes. Each mandrel, about which a tube is made, is positioned between two pairs of disks spaced from each other a distance substantially equal to the diameter of the mandrel plus the thickness of the strips. The strips are fed into the apparatus, one on each side, and into contact with the disks 112 which are rotated towards each other, the peripheries of the disks being in substantially abutting relation.

The movement of the disks moves the strips into contact with the mandrels and the disks engage the two strips in between the mandrels so as to press them together to unite the strips into one or more tubes depending upon the number of mandrels used.

It will thus be seen that the apparatus is so constructed and arranged that when two substantially flat strips of gelatinous material of a width at least equal to the distance between the pairs of disks are fed into the bights between the disks of each pair and on opposite sides of the mandrel or mandrels, the strips are contacted and moved around the mandrel or mandrels and pressed together by the peripheries of the disks to unite the strips into the form of a tube or a plurality of tubes. When a plurality of tubes are made, the pairs of disks are separated from each other a distance substantially equal to the diameter of the mandrel plus twice the thickness of the strips. The mandrels are hollow so that medicament may be passed through them and into the tubes while the tubes are being made. These tubes, when made, are used for the purpose of

making capsules filled with medicament, as set out for example in my application filed July 25, 1939, Serial No. 286,315, being a continuation of application No. 99,886, filed September 8, 1936.

5 The hollow mandrels may have their lower ends 115a wedge shaped to provide annular shoulders 116 or they may be of some other form such, for example, as shown in my prior application above noted.

Now having described the various tube forming means disclosed herein, reference will be had to the claims which follow for a determination of the invention hereof.

I claim:

15 1. An apparatus for transforming substantially flat strips of gelatinous material into a tube comprising a hollow mandrel, spaced pairs of rotatable disks, said mandrel being positioned between two of said pairs of disks, and said pairs of disks being spaced from each other a distance substantially equal to the diameter of the mandrel plus twice the thickness of the strips, the peripheries of the disks of each pair being in substantially abutting relation, said disks and mandrel being 20 so constructed and arranged that when two substantially flat strips of said mandrel of a width at least equal to the distance between the pairs of disks are fed into the bights between the disks, of each pair and on opposite sides of the mandrel, 25 the strips are contacted and moved around the mandrel and pressed together by the peripheries only of the disks to unite the strips into the form of a tube.

2. An apparatus for transforming substantially 35 flat strips of gelatinous material with a plurality of tubes comprising a plurality of hollow mandrels a plurality of spaced pairs of rotatable disks, each mandrel being positioned between two of said pairs of disks, and said pair of disks being 40 spaced from each other a distance substantially equal to the diameter of the mandrel plus twice the thickness of the strips, the peripheries of the disks of each pair being in substantially abutting relation whereby when two substantially flat strips of said material of a width at least equal to the distance between the pairs of most widely spaced apart disks are fed into the bights between the disks, of each pair and on opposite sides of the mandrels, the strips are contacted and moved 45 around a plurality of the mandrels and pressed together by the peripheries only of the disks to unite the strips into the form of a plurality of tubes.

REX E. MOULE.
